PLIERS FOR BENDING CONNECTING CLIPS
ABOUT WIRE MEMBERS

George W. Mount, Greenfield, Mass.

Application June 6, 1949, Serial No. 97,334

1 Claim. (Cl. 81—15)

1

This invention relates to improvements in pliers for securing two lengths of wire together in generally parallel relation.

In the fabrication of structures comprising coiled wire spring assemblies for various purposes, it is customary to upset a metal clip around substantially parallel portions of wire members to hold the assembly together. For example, in coiled wire spring assemblies for beds, couches, and similar articles the coiled springs are connected together by wires secured to the top convolution of adjacent springs by metal clips. These metal clips are of generally channel form and the edge portions which are formed with staggered projections, are bent toward each other and around the wire and the end convolution of the spring by pliers having jaws which engage the edge extensions of the clip.

The object of the invention is to provide an improved construction for such pliers which will make possible a tighter and more efficient connection of the wire to the spring over a wider range of sizes of the wire and spring.

In the accompanying drawings,

Fig. 1 is a side elevational view of the head portion of a pair of pliers embodying the invention;

Fig. 2 is a top plan view of the structure shown in Fig. 1;

Fig. 3 is a detail sectional view substantially on line 3—3 of Fig. 2 of the bridge element of the pliers;

Fig. 4 is a detail, generally perspective view of the form of clip applied by the pliers;

Fig. 5 is a diagrammatic view showing the pliers adjusted for securing a wire of relatively small cross section to a spring formed of wire of relatively small cross section;

Fig. 6 is a similar view showing the pliers adjusted for an intermediate size of wire and spring; and

Fig. 7 is a similar view showing the pliers adjusted for a relatively large wire and spring.

Referring to the drawings, the pliers are shown as comprising two plier members 1 and 2 pivotally connected together by a U-shaped member, generally indicated at 3, which is pivoted at 4 and 5 to the members 1 and 2. The cross members 6 of member 3 is grooved at 7 to form the saddle member of the pliers. A compression spring 8 is suitably engaged between the members 1 and 2 above the pivots 4 and 5 to normally hold the pliers open. The head end of member 2 is formed with projection or jaw 9 adapted to enter between spaced projections or jaws 10 formed on the head end of member 1. Positioned in the saddle groove 7

2

is an elongated strip 11 releasably secured in the groove by a U-shaped spring member 12 having inturned ends 13 adapted to be releasably engaged over shoulders 14 formed in member 3 below the ends of saddle groove 7. As best shown in Fig. 1, the upper surface of spring member 12, when member 11 is positioned beneath it, lies slightly below the upper edges of the saddle groove.

In operation a deformable clip 15, such as shown in Fig. 4, is positioned in the saddle groove 7 as shown for example in Fig. 5. The clip 15 has a trough portion 16 from one side edge of which projects a tongue 17 adapted to be positioned in front of jaw 9, the opposite edge of the clip being formed with spaced extensions 18, which lie in the path of jaws 10 of the pliers. The length of wire 19 and the portion 20 of the top convolution of a coil spring to which the wire is to be attached are positioned in the trough portion 16 of the clip. Usually, the clip is formed with inwardly extending bosses 21 which maintain the portions of wire 19 and spring 20 which are within the clip adjacent the sides of the latter. As will be obvious in Fig. 5 inward movement of the projections 9 and 10 will bend the extensions 17 and 18 of the clip over and onto the wire 19 and spring 20, as shown in dotted lines, to secure them together. For the best operation the upper sides of the wire and spring should be positioned closely adjacent the level of the lower edges of the jaws 9 and 10 so that as the jaws 9 and 10 bend the extensions of the clip toward each other the extensions are bent tightly over the wire and spring, the latter being moved toward each other and up the sides of the bosses 21, the latter acting as wedges to form a tight assembly.

When the wire and spring are of larger cross section than that illustrated in Fig. 5, the desired relationship of the jaws 9 and 10 with the upper face of wire and the coil spring may be obtained by removal of member 11 from beneath the spring clip 12 as illustrated in Fig. 6; and where the wire and spring are of still larger cross section both the spring 12 and member 14 may be removed as in Fig. 7, to maintain the desired relationship between the jaws 9 and 10 and the upper surfaces of the wire and spring.

What I claim is:

A pair of pliers for bending clips about wire members which comprises a saddle member, a pair of plier members pivoted to said saddle member for movement toward each other, said plier members being provided with interfitting jaws, a groove formed in the saddle member for receiving a clip having upstanding sides engageable by the

jaws, shoulders formed on the saddle member at the ends of the groove, a flat spacing member positioned in said groove, and a flat spring member having inwardly turned end portions engaging the end faces of the saddle member below said shoulder for releasably retaining the spacer and the intermediate portion of the spring in said groove, the combined thickness of said spacer and spring being slightly less than the depth of the groove.

10 GEORGE W. MOUNT.
